UNITED STATES PATENT OFFICE

2,611,373

RIDER PLATE CONSTRUCTION

Joseph A. Neumair, Hollis, N. Y., assignor to International Cigar Machinery Company, a corporation of New Jersey

Application December 5, 1945, Serial No. 632,836

4 Claims. (Cl. 131—52)

1

This invention relates to cigar machines, more particularly to improvements in bunch rolling mechanism of the type disclosed in the patent to H. H. Wheeler, 2,311,011, issued February 16, 1943. In this type of bunch rolling mechanism the bunch rolling pin is provided with a rider plate which is pivotally mounted on the rolling pin and is maintained in a forward position while the rolling pin advances a loop in the rolling apron across the rolling table. While the loop in the apron is being advanced by the rolling pin, the rider plate holds the bunch charge down upon the rolling apron to cause the charge to be coiled upon itself. The rider plate is subsequently swung to a rearward position, the rolled charge is then rolled within a binder positioned on the apron, and the rolling pin is returned with the rider plate to its initial position. However accumulations of paste and tobacco on the rolling apron may interfere with the return movement of the rider plate to its initial position and cause it to assume an upwardly inclined position instead of its normal horizontal position. Therefore when the rider plate reaches its initial position it may interfere with the passage of the bunch charge thereover onto the rolling apron.

One of the main objects of this invention is to prevent interference with the return movement of the rider plate to its initial position by accumulations of paste or tobacco on the rolling apron. To this end the rider plate may be eccentrically mounted on the rolling pin so that the clearance between the rolling pin and rider plate will be increased sufficiently to permit passage of the rolling apron therebetween without interference by accumulations of paste or tobacco on the rolling apron when the rider plate is returning to its initial position.

A further object of the invention is to adjust the rider plate relatively to the rolling pin to vary the clearance between the rider plate and rolling pin. Heretofore the clearance between the rolling pin and plate was not adjustable. Occasionally, during the coiling of the charge upon itself while the rolling pin moved the loop in the apron forwardly and the charge was held against the apron by the rider plate, tobacco would escape through the gap between the rider plate and rolling pin. Moreover, when rolling aprons of different thickness were used the movement of a thicker apron through the gap between the pin and plate was effected with difficulty. With my adjustable mounting of the rider plate the size of the gap between the rider plate and rolling pin may be varied to permit thicker rolling aprons to freely pass through said gap. More-

over the size of this gap may be regulated to vary the clearance sufficiently to prevent the escape of tobacco while the charge is held down by the plate and being coiled upon itself.

5 With these and other objects not specifically mentioned in view the invention consists in certain constructions and combinations which will be hereinafter described and fully set forth in the appended claims.

10 In the accompanying drawings which form a part of this specification and in which like characters of reference indicate the same or like parts:

Fig. 1 is a longitudinal sectional view of the mounting of the rider plate and the rolling pin.

Fig. 2 is a sectional view taken on the line 2—2 of Fig. 1 showing the rider plate in its rearward position.

Fig. 3 is a similar view showing the rider plate 20 in its forward position.

Fig. 4 is an end illustration on a much smaller scale than Figures 1—3 of a cigar bunch rolling mechanism equipped with my improved rider plate.

25 Referring to Fig. 1 of the drawings, it will be seen that the rolling pin 10 is revolvably mounted on bearings 12 carried by a shaft 14 provided with eccentric trunnion 15 and eccentric trunnion or pintle 16. The trunnion 15 is supported in the upper end of a bracket 18 fastened at its lower end as shown in Fig. 4, to the bottom of slide 20 which will later be described more fully. Trunnion 15 is concentric with the trunnion or pintle 16, and trunnion or pintle 16 is also concentric with shaft 24 having a head 22 in which trunnion 16 is supported. Shaft 24 is carried in the upper end of a bracket 26 which is fastened at its lower end to the slide 20.

One corner of a rider plate 30 is fastened to a flattened portion 32 on a collar 34 rotatably mounted on trunnion 15. The other corner of plate 30 is similarly secured to the head portion of shaft 24.

40 A slotted block 171 (Fig. 4) supports the base 172 of the bunch rolling table (not shown) whose construction is fully described in Wheeler Patent 2,311,011 to which reference may be had for description of the rolling table. Block 171 also supports the slide 20 which is provided with guide rollers 175 engaging slots in base 172. Bracket 18 carries a ball stud 181 which is connected by a link (not shown) to a cam lever (not shown) which reciprocates the slide 20 on block 171 and thereby moves the rolling pin to and fro along 45 50 55 the bunch rolling table.

On the base 172 are fastened brackets 199 which carry the shaft 200 of a drum 201 which is provided with a longitudinal notch in which one end of the rolling apron 202 is secured. The rolling apron extends across a platform (not shown), which supports the bunch charge while it is being coiled upon itself and thence along the length of the bunch rolling table to which its outer end is clamped. The shaft 200 carries a sprocket 204, which is intermittently driven by a sprocket chain 205, to tighten and slacken the rolling apron. One of the brackets 199 has a bearing 207 in which is journaled a shaft 206 carrying on one of its ends an arm 208 which is connected by links (not shown) to a platform (not shown) arranged in front of the rolling table. The platform may have a perforated top and a suction chamber so that the overlying portion of the apron adheres to the platform when it is lowered whereby a loop is formed in the apron. On the other end of the shaft 206 is secured an arm 222 which is connected by a rod 233 to a cam lever (not shown). Suction may be maintained in the platform (not shown) by suitable ducts communicating with a pipe 217 connected to the suction system of the cigar machine. Since the construction of the platform and the mechanism for reciprocating slide 20 is fully described in Wheeler Patent 2,311,011, further description thereof is deemed unnecessary.

When the brackets 18 and 26 move the rolling pin rearwardly to its initial position in front of the suction platform, a flattened portion 186 formed on the outer end of shaft 24 engages a slot in a shaft 187 supported in a stationary pedestal. Shaft 187 is then turned by mechanism described in Wheeler Patent 2,311,011 to swing the rider plate 30 through 180 degrees to its forward position shown in Fig. 3. On the portion of shaft 24 projecting from bracket 26 is clamped an arm or finger 193, which engages a stationary roller 194 (Fig. 4) while the rolling pin is moving forwardly across the rolling table, and the rider plate is thus swung back to its rearward position shown in Fig. 2. The roller 194 is mounted in an arm 195. Since the construction of the stationary roller 194 and arm 195 is fully described in Wheeler Patent 2,311,011 further description thereof is deemed unnecessary.

The bunch charge is advanced by a charge transfer, whose construction is shown in said Wheeler patent, across the rider plate 30 while same is in its rearward position and the rolling pin is in its initial position to deposit the bunch charge on the portion of the rolling apron overlying the platform. The rider plate is then swung to its forward position after the platform has descended with the portion of the rolling apron adhering thereto and formed the loop in the apron required for coiling the charge. While the rider plate is being swung forwardly the drum 201 is turned forward by chain 205 to pass out a length of the rolling apron 202 sufficient for the formation of the loop shown in Fig. 3. The forward movement of the rolling apron to permit formation of the loop is indicated by the arrow in Fig. 2.

While in its forward position the rider plate acts to hold the charge down upon the rolling apron while it is being rolled upon itself during the forward movement of the rolling pin. The drum 201 then turns backward to tighten the apron about the coiled charge, and the arm 193 engages the stationary roller 194 to swing the

rider plate into its rearward position. As the rolling pin moves to its extreme forward position, the charge is rolled within a binder deposited on the portion of the rolling apron overlying the bunch rolling table to form the cigar bunch. The cigar bunch is tightened by a final backward turn of drum and delivered from the loop of the apron ready to be transferred to the bunch shaping and wrapping mechanism.

10 Since the rider plate is in its rearward position while the rolling pin is being returned to its initial position, the clearance between the rolling pin and rider plate is sufficiently great to permit passage of the same over the rolling apron without interference by accumulations of paste or tobacco on the rolling apron. Therefore the rider plate will be returned to its initial position without being displaced from its horizontal position shown in Fig. 3.

15 While the clearance between the rolling pin and rider plate is much smaller when the rider plate is at its forward position this clearance may be enough to permit tobacco to escape therethrough from the bunch charge being coiled upon itself in the loop of the apron. This clearance may be reduced to prevent the escape of tobacco by unloosening the set screw 115 holding the trunnion 15 in bracket 18 and turning trunnion 15 until the clearance is diminished sufficiently to prevent escape of tobacco therethrough. If the clearance is too small to permit free passage therethrough of the rolling apron, the trunnion is turned in the opposite direction. After either 20 of these adjustments the set screw 115 is tightened to hold the rider plate in the adjusted position.

25 What is claimed is:

1. In a cigar bunch rolling mechanism, the combination with a rolling apron adapted to support a bunch charge, of a rolling pin adapted to move a loop in said rolling apron forwardly to cause the loop to coil the bunch charge upon itself and then roll the rolled charge within a binder positioned on the rolling apron, said rolling pin being provided with eccentric trunnions, a movable support in which said trunnions are mounted, a rider plate pivotally mounted on the trunnions of said rolling pin adapted to be 30 swung from a rearward position into a forward position overlying the bunch charge on the apron to hold the same while it is being coiled upon itself, the clearance between said pin and plate being greater when the plate is at its rearward position than at the forward position 35 thereof, means for moving said support forwardly while said rider plate is in its forward position to roll said charge upon itself and within a binder and then return said support with 40 said rolling pin and rider plate to an initial rearward position, and means for swinging said plate from a rearward to a forward position and to a rearward position during the forward movement of said support and subsequently swinging said plate to a forward position at the rearward position of said support, the rolling apron extending between said rider plate and rolling pin whereby when said plate is swung rearwardly the clearance between the same will be sufficiently increased to permit passage of the rolling apron therebetween, while said support returns to rearward position, without interference by accumulations of paste and tobacco on said apron.

70 2. In a cigar bunch rolling mechanism, the

combination with a rolling apron adapted to support a bunch charge, of a rolling pin adapted to move a loop in said rolling apron forwardly to cause the loop to coil the bunch charge upon itself and then roll the rolled charge within a binder positioned on the rolling apron, said rolling pin being provided with eccentric trunnions, a movable support in which said trunnions are mounted, a rider plate pivotally mounted on the trunnions of said rolling pin adapted to be 10 swung from a rearward position into a forward position overlying the bunch charge on the apron to hold the same while it is being coiled upon itself, the clearance between said pin and plate being greater when the plate is at its rearward position than at the forward position thereof, means for moving said support forwardly while said rider plate is in its forward position to roll said charge upon itself and within a binder and then return said support with said rolling pin 20 and rider plate to an initial rearward position, means for swinging said plate from a rearward to a forward position and to a rearward position during the forward movement of said support and subsequently swinging said plate to a forward position at the rearward position of said support, the rolling apron extending between said rider plate and rolling pin whereby when said plate is swung rearwardly the clearance between the same will be sufficiently increased to permit passage of the rolling apron therebetween, while said support returns to rearward position without interference by accumulations of paste and tobacco on said apron, and mechanism permitting adjustment of said rolling pin relative to said rider plate to vary the clearance between the rolling pin and rider plate at the forward position of said plate.

3. In a cigar bunch rolling mechanism, the combination with a rolling apron adapted to support a bunch charge, of a rolling pin adapted to move a loop in said rolling apron forwardly to cause the loop to coil the bunch charge upon itself and then roll the rolled charge within a binder positioned on the rolling apron, said rolling pin being concentrically mounted for rotation about a shaft, said shaft being provided with eccentric trunnions, a movable support in which said trunnions are mounted, a rider plate mounted for oscillation on and about the trunnions of said shaft adapted to be swung from a rearward position into a forward position overlying the bunch charge on the apron to hold the same while it is being coiled upon itself, the clearance between said pin and plate being greater when the plate is at its rearward position than at the forward position thereof, means for moving said support forwardly while said

5 rider plate is in its forward position to roll said charge upon itself and within a binder and then return said support with said rolling pin and rider plate to an initial position, means for swinging said plate to a rearward position during the forward movement of said support and subsequently swinging said plate to a forward position at the rearward position of said support, the rolling apron extending between said rider plate and rolling pin whereby when said plate is swung rearwardly about said trunnions the clearance between the same will be sufficiently increased to permit passage of the rolling apron therebetween, during the return movement of said support to a rearward position, without interference by accumulations of paste and tobacco on said apron.

4. In a bunch rolling mechanism of a cigar making machine wherein a means is provided 20 for swinging an apron support to and from a bunch rolling position, said means comprising a slidable support, aligned bearing openings in said slidable support, a support for a rider plate having a shaft concentrically mounted in one 25 of said openings, a support for a roller having a shaft concentrically mounted in the other of said openings said latter shaft having an eccentric cylindrical extension between the first shaft and the concentric mounting of the second shaft, said roller being mounted on the cylindrical extension and said extension having a pintle, said first shaft having a bore to receive the pintle, the axis of the pintle and the axis of the second shaft being coaxial, said second 30 shaft being adjustably mounted in said slidable support, means for maintaining the second-named shaft in adjusted positions relative to the slidable support and means for oscillating the first-named shaft, a rider plate fixed to the first shaft and oscillatable on the second shaft from an initial upper position to a lower position, whereby in the upper position the roller will maintain an apron thereon in appreciably spaced relationship to the rider plate and in its 35 lower position substantially in contact with the rider plate.
